UNITED STATES PATENT OFFICE.

HARRY L. BEACH, OF COSHOCOTON, OHIO.

SHEET-METAL SHELF.

No. 889,844.

Specification of Letters Patent.

Patented June 2, 1908.

Application filed September 15, 1906. Serial No. 334,730.

To all whom it may concern:

Be it known that I, HARRY L. BEACH, a citizen of the United States, residing at Coshocton, in the county of Coshocton and State 5 of Ohio, have invented a new and useful Sheet-Metal Shelf, of which the following is a specification.

This invention relates to improvements in display shelves, and the principal object is to 10 provide an advertising novelty of the above character, which can be cheaply manufactured, can be readily placed in a show-window or other exposed location to display goods, is thoroughly braced and strengthened, and at the same time is provided with 15 means for displaying advertisements, and the like.

The preferred form of construction is illustrated in the accompanying drawings, where- 20 in:—Figure 1 is a perspective view of the shelf. Fig. 2 is a longitudinal sectional view therethrough. Fig. 3 is a cross sectional view showing the shelf provided with a retaining rib. Fig. 4 is a cross sectional view 25 of a modified form of construction. Fig. 5 is a plan view of a portion of the shelf shown in Fig. 4.

Similar reference numerals designate corresponding parts in all the figures of the 30 drawings.

In the embodiment illustrated in Figs. 1 and 2, the shelf body is formed from a single piece of sheet metal, comprising a shelf plate 6, having depending side flanges 7, and de- 35 pending end flanges 8. These flanges serve to prevent the buckling of the plate 6 either longitudinally or transversely. The side flanges 7 are preferably of considerable width, and their lower margins are offset, as shown 40 at 9, so as to brace them, and at the same time, give an ornamental appearance to the same. These flanges 7 are of sufficient width to permit advertising matter to be placed thereon, as shown in Fig. 1. The different 45 flanges can be formed into various designs in order to produce a highly ornamental shelf.

Arranged between the flanges and across the under side of the plate 6, are reinforcing strips 10 preferably of wood. Screw eyes 11, 50 passed through the plate 6, are threaded into the strips, serving to hold them in place, said strips at the same time, providing extended bearings for the supporting chains, designated respectively 12 and 13. In the preferred form of construction, the chains 12 are 55 of considerable length so that their upper

ends may be fastened to a ceiling or other support, while their lower ends are fastened to the screw eyes at one side of the plate. The chains 13 on the other hand are compar- 60 atively short, their lower ends being connected to the screw eyes at the other side of the plate, and their upper ends having hooks 14 that are arranged to adjustably engage the chains 12 so that the shelf may be sus- 65 pended in a horizontal position or at different inclinations, as will be evident. As a result, it will be evident that an exceedingly simple shelf is provided of ornamental appearance, which can be readily suspended in practically 70 any place desired, and while constituting a strong and efficient support for articles, will display an advertising sign.

Instead of a perfectly flat shelf, as shown in Fig. 1, upstanding ribs 15 may be formed 75 upon the marginal portions of the plate as shown in Fig. 3, so as to prevent articles placed thereon from sliding therefrom, or as shown in Figs. 4 and 5, the plate 6 may be provided with upturned lips 16, and thus if 80 the shelf is placed at an inclination, as illus- trated in Fig. 4, articles arranged thereon will be securely held in place. Otherwise the structure of the shelves shown in Figs. 3 and 4 is the same, as that disclosed in Figs. 1 and 85 2, and therefore the same reference numerals have been employed. These modifications are merely indicative of the changes that may be made, and it will be evident that other alterations in the shape, size, propor- 90 tion, and minor details of construction may be resorted to without departing from the spirit or sacrificing any of the advantages of the invention.

Having thus fully described my invention, 95 what I claim as new, and desire to secure by Letters Patent, is:—

1. As an article of manufacture, a sheet metal plate having depending reinforcing flanges along its opposite margins, spaced 100 reinforcing strips located against the under side of the plate and disposed between and transversely of the flanges, and supporting means including devices that pass downwardly through the plate and are engaged 105 with the strips.

2. As an article of manufacture, a sheet metal plate having depending reinforcing flanges along its opposite margins, spaced 110 reinforcing strips located against the under side of the plate and disposed between and transversely of the flanges, and eyes located

above the plate and having shanks passing through the same and engaged with the ends of the strips, said eyes constituting means for securing the strips to the plate and also 5 constituting means for fastening the supporting means to said plate.

In testimony, that I claim the foregoing as

my own, I have hereto affixed my signature in the presence of two witnesses.

HARRY L. BEACH.
